APPARATUS FOR HEAT TRANSFER
BETWEEN FLUIDS

Charles A. Phipps, Hartsdale, N. Y.; Frank Northern Magill, executor of said Charles A. Phipps, deceased, assignor to Carolyn Magill Phipps, Hartsdale, N. Y.

Application November 16, 1946, Serial No. 710,255

9 Claims. (Cl. 62—140)

1
This invention relates to apparatus for passing heat through partition members separating two fluid streams, and more particularly for passing heat from one stream to another through heat exchange surfaces arranged in the general form of a convolute.

An object of this invention is to provide heat exchange apparatus in which a major portion of the total surface area enclosing the two fluid streams is common to both streams, thus increasing the exchange of heat between the streams.

Another object of this invention is to provide an improved wiping effect of the heat exchange surfaces throughout the flow of both fluids within the heat exchange apparatus, thus increasing the rate of heat transfer per unit of surface area.

A further object of this invention is to provide a very efficient heat exchange apparatus in a relatively small space.

Still further objects are to provide an improved design of a heat exchanger element suitable for use with gases without the use of fins, and which provides economies of manufacture not available in present heat exchange equipment.

The transfer of heat between separate fluids of substantially different densities, such as between water and air, is ordinarily cared for by passing the more dense fluid through metal tubes, and passing the less dense fluid in contact with the external surface of the tubes, which may be greatly increased in effective surface area by the addition of ribs, fins or the like. However, this construction is not well adapted for use with two fluids of approximately equal density, such as between cool and warm air; for which efficient design requires that each stream have approximately the same amount of effective surface in heat exchange relationship with the fluid.

The use of ordinary round tubing, ducts or the like without fins to obtain approximately equal surface area in contact with both streams is uneconomical. This is due to the fact that, for a given capacity of fluid flow within the tube, a round tube presents the least possible surface area in heat exchange contact with the fluid and ordinarily flattened tubes do not greatly extend the area. It is, of course, desirable to improve this condition by providing a maximum of such surface area in a very economical manner. The present invention accomplishes this desired result.

In the usual heat exchange apparatus, certain

2
surfaces are ordinarily conceded to be provided for other purposes than for the direct exchange of heat, and are not included in the computations for heat exchange capacity. Such surfaces may include baffles, the outer shell, and other miscellaneous surfaces. The present invention holds such non-transfer surfaces to a minimum, and comprises an arrangement whereby a very large part of the total surface area is in direct heat exchange relationship with both fluids. This produces a more efficient heat exchange unit with regard to initial cost, total space occupied, and heat transfer per unit of material used.

These advantages are obtained by a novel construction in which two longitudinal members of relatively thin heat conducting material of approximately equal width, such as sheet metal, are positioned with two of their principal surfaces parallel, forming a space between them suitable for continuing the flow of one of the fluids. In addition to this spacing, the two members are also positioned so that, in a view showing their longitudinal edges, they are, in the general form of a double-wound spiral or convolute. This positioning is such as to provide a second space between the turns of the spiral, which brings the other two principal surfaces into opposition, with the space between them suitable for containing the flow of the second fluid.

The two spaces thus provided comprise the walls of two separate passages from the outer edge of the spiral to the vicinity of its center. This structure, in its several modifications described in the present application, is referred to as a "convolute."

To complete the closure of the passages, the two open ends formed by the longitudinal edges of the metal sheets may be capped by any suitable covering, such as a soldered closure. However, this capping may be accomplished with greater speed and economy of manufacture by fastening an insulating board or other rigid member, faced with a resilient moisture-proof gasket or cement, such as a mastic or rubber-like material, over each of the two open ends. Such capping also includes the advantage of ready accessibility to the interior for cleaning, inspection of controls, etc.

The two fluids may be introduced into and withdrawn from their respective passages by suitable ducts at the outside and center terminations of the convolute. The flow may be 55 in either direction in each passage as required.

Thus, parallel flow of the two fluids or counter flow may be employed as is most suitable for specific applications.

In a modification of this arrangement, the termination at the center of the convolute may be such as to merely reverse the flow of a single fluid which has entered through one of the passages, and to thereby direct the same fluid outwardly through the other space, thus placing the fluid in reverse flow relationship with other portions of the same stream. This is advantageous, for example, in the dehumidifying of air. The entering air is precooled by heat transfer as it flows toward the center of the convolute. At or near the center, a cooling means such as an evaporator coil of a refrigerating apparatus is provided to establish a temperature differential between the inward-flowing and outward-flowing portions of the stream; then as the air flows outwardly through the other passage, it is reheated by the same heat transfer that is precooling another portion of the entering stream. The total cooling effect of the precooling and the refrigerating of the entering air is sufficient to cause its temperature to fall below its dew point and to precipitate moisture; the air leaving the convolute is reheated during its outward travel so as to be more readily usable than cold air; and the load on the refrigerating apparatus may be economically limited to that required to provide an adequate temperature differential across the heat transfer surfaces, and to remove the latent heat released by the condensation of moisture, at a considerably large saving of refrigerating equipment.

A generally similar arrangement may be used to conserve heat in chemical or distillation processes. For example, a fluid may be preheated by heat transfer as it flows inwardly toward a heating means located in the vicinity of the center of the convolute; and subsequently, it may give up part of its heat to other entering fluid. In such applications, the convolute may, in effect, be incorporated in the walls of a vessel.

In order to provide improved wiping action of both the inward-flowing and the outward-flowing streams, and to provide increased heat transfer surface at low cost, indentations may be pressed into the metal sheets in a manner to not unduly obstruct the flow of the fluid nor to form pockets of lowered velocity. Such indentations would preferably be arranged to deflect the fluid alternately in one direction and then the other so as to increase the wiping action of the fluid against the heat transfer surfaces on both sides of the passage. Such indentations are preferably in the form of a pattern of blisters designed to face alternately toward each surface of the sheet in which they are pressed, and to be staggered to avoid any substantially straight flow of fluid between two of these sheets. A pattern of such blisters may be impressed in the metal sheets cheaply by passing the sheet between a pair of forming rolls, or by the use of suitable dies or the like. Although corrugations may be used, they are not as satisfactory as a pattern of blisters or similar protrusions. This is because corrugations require a greater length of original stock. They also cause undue restriction of narrow passages in locations where the protruding ridges fall opposite to one another. The valleys of the corrugations provide pockets of lowered fluid velocity, tending to reduce the rate of heat transfer.

The improved heat transfer element of this invention, provided with localized concave and

convex projecting curved surfaces which are each much smaller than the width of the element or sheet, and which project in alternate directions from the surfaces along both its length and width, can then be rolled even tightly on itself, in the form of a smooth spiral or in any irregular shaped convolute, without blocking of the air passages between the surfaces. Even when tightly wound on itself, the surfaces of adjacent turns can come in contact at only a few scattered points. Generally in use it is preferred to separate the turns by a distance slightly greater than twice the height of the projections, so that they do not actually touch at any point in order to avoid direct transfer of heat by conduction from wall to wall.

An alternative modification of the present invention comprises the soldering of cooling or heating coils directly to the heat transfer surfaces in the vicinity of the center of the convolute, thereby increasing the heat absorbing or heat dissipating area of such coils, and providing an economical and efficient means for introducing a temperature differential when a convolute is used for reverse flow of the same fluid.

All of the foregoing description uses the general spiral form as the simplest variation of the present invention. However, the overall shape of the complete heat exchange unit may be varied to fit into a particular available space. For example, if a long and relatively thin space is available, the heat exchange unit may be modified to fit into the space by introducing straight lengths of metal sheets, with the curvature at the ends arranged to provide the spiral effect of inward and outward passages. Such an elongated unit may, in turn, be constructed with bends along its length to conform with the shape of whatever space is found to be available. Thus, such over-all shapes as a U-shaped unit, an L-shaped unit, etc. may be readily produced while retaining the basic improvement of the present invention.

The drawings presented herewith are illustrative of several modifications of the present invention. The same numerals represent similar elements throughout the several figures.

Figure 1 is a diagrammatic sketch in sectional plan of a heat exchange unit in the form of a convolute.

Figure 2 is a modification of Figure 1, in which the convolute is elongated by the introduction of substantially straight sections of heat exchange surface.

Figure 3 is a modification of Figure 2 in which an elongated convolute is curved to conform with a required external shape.

Figure 4 is a modification of Figure 1 in which the convolute is incorporated in the walls of a vessel, with provision for additional heat transfer between the vessel and an external heat supplying or receiving zone.

Figure 5 is another modification of Figure 2 in which the central portion of the convolute has means for providing a temperature differential.

Figure 6A is a section on line A—A of Figure 6B. It is a diagrammatic sketch in sectional plan of a typical pattern of indentations in the walls of a convolute of any of the types illustrated in Figures 1 to 5, inclusive, to increase the transfer of heat through the walls. Figure 6B is a similar elevation view of Figure 6A taken from line B—B.

Figure 7 is a section on line C—C of Figure 8. It is a diagrammatic sketch in partial sectional

elevation of the convolute of Figure 8, in which the ends are closed by an arrangement of gaskets, substantially rigid members and bolts. Figure 8 is a diagrammatic sketch in partial sectional plan of a device for drying air in accordance with the present invention.

Referring to Figure 1, two heat exchange surfaces are represented by edges 1 and 2 viewed in sectional plan. These surfaces are separated by space 3, which is suitable for containing a fluid stream passing in either direction between ends 5 and 6 of space 3. The two surfaces 1 and 2 are curved to form a convolute, thus also forming space 4, which is suitable for containing a second fluid stream passing in either direction between ends 7 and 8 of space 4. A suitable closure is provided over the edges of the heat exchange surfaces, as described later, to prevent the escape of either fluid except at 5, 6, 7 or 8. The two passages 3 and 4 may be connected at their inner ends 6 and 8 to separate fluid conduits 9 and 29, as illustrated in Figure 1, or they may connect directly with each other, thus reversing the flow of fluid on itself through the convolute, as shown in Figures 2-5 and 8.

Referring to Figure 1, assuming one fluid stream to enter at 5, and another at 8, the two fluids in this case move in counter-flow, emerging at 6 and 7, respectively. Throughout the major portion of the travel of the stream entering at 8, both of the heat exchange surfaces forming the walls of space 4 are in direct heat exchange relationship with the fluid stream in space 3. Similarly, the fluid stream entering at 5 is in contact with heat exchange surfaces 1 and 2 throughout its travel. The arrangement is preferably such that the flow of heat to or from the surrounding air through that part of surface 1 forming the outer shell is favorable by passing the warmer or the cooler fluid through space 3, as may be desired. Otherwise this outer shell may be insulated. The remaining areas of heat exchange surfaces 1 and 2 are all in direct heat exchange relationship with the other fluid in space 4. This provides an arrangement with a very high proportion of the total surface area in direct heat exchange relationship with both fluids, and the amount of such surface may be readily increased by adding turns without increasing the outer shell area in the same proportion.

This arrangement also gives a choice of parallel flow or counter flow, and a choice between points of entrance and discharge of each fluid so as to take the maximum advantage of the available temperature differentials and to thus obtain the greatest flow of heat.

The arrangement is economical of metal because it is made by forming flat sheets, which are not only cheaper to produce than other types of surface, but also may be used in thinner gauges than are ordinarily available in the walls of tubes or the like.

In case a cylindrical overall shape is not suitable, the convolute may be modified in any of several ways to conform with the limitations of an available space.

For example, Figure 2 illustrates an elongated heat transfer unit similar to that illustrated in Figure 1, except that the introduction of substantially non-curved heat transfer surfaces has extended its length. This increases the heat transfer capacity of the unit. If it is desired to provide an elongated unit of equivalent capacity to that of a cylindrical unit per Figure 1, the width of the heat transfer surfaces or the radii

of curvature at the ends, or both, may be reduced. This provides flexibility of design to meet the conditions of practical applications. In such designs it is desirable to provide an extension of one heat exchanger surface strip around the end of the other, as at 19, to provide for maximum utilization of the available surface for heat exchange.

A further advantage of an elongated unit as shown in Figure 5, is that cooling or heating coils 10 may be readily fastened to any of the non-curved heat transfer surfaces to provide a desired temperature differential, or where passages 5 and 7 do not connect at the center, to control the precooling or preheating effects as may be desired.

Figure 3 is illustrative of further modifications of the overall shape of the heat transfer unit. In this case, it is assumed that the available space for heat transfer equipment is in the shape of an L and that a unit generally similar to that illustrated in Figure 2 is provided with curved elongated surfaces to meet this requirement. Such surfaces may, for example, be curved to provide an overall U shape, S shape, or other desired shape of the heat exchange unit to meet the requirements of practical applications in restricted spaces, while retaining the characteristic high capacity of heat transfer provided in this general type of unit.

Figure 4 illustrates a modification of Figure 1 suitable for preheating or precooling a fluid stream as it approaches a vessel at the vicinity of the center of the convolute, by heat exchange from a fluid stream leaving the vessel. This is suitable for economically operating a continuous process requiring the heating of a fluid, which may include chemical processing, food processing, distilling, crystallization, and the like. Such operation may be conducted in the space 38, which may be provided with suitable means for removing a solid, liquid or vapor phase from the fluid passed therethrough. This device is also applicable for the cooling and reheating of a fluid in a continuous process, such as the cooling and reheating of air in a dehumidifying process. In such cases, a cooling means such as a refrigerating coil 10 is provided in heat exchange relationship with the fluid in the vessel. In all such constructions the convolute may be built into, or may itself form the wall of the vessel.

The convolute of Figure 4 may be similar to that illustrated in Figures 1 or 2, with the inner terminations 6 and 8 opening into the walls of the vessel. Suitable baffles 14 may be provided to assure that the fluid remains in the vessel for a sufficiently long period to complete the process in accordance with the needs of specific applications.

Figure 5 illustrates an elongated unit in which an arrangement is provided in the vicinity of the center of the convolute whereby the same fluid is redirected into the second passage, to provide for heat exchange between the entering and the leaving portions of the stream. This modification is suitable for application in those cases for which a vessel is not required but reversal of the fluid stream is necessary; or in cases where the overall thickness of the elongated heat exchange unit in a reversed-flow application is a limiting factor. It is also of value where economy of manufacture is improved by the use of only two continuous members to provide the outer shell, the heat exchange surfaces, and the reversing means. This arrangement also provides a convenient and eco-

nomical mounting means for heating or cooling coils 10, which may be in the form of finned radiator tubes or may be soldered to one or more of the substantially straight heat exchange surfaces in the vicinity of the center of the convolute to provide the necessary temperature differential between the entering and the leaving fluids.

Figure 6A illustrates a section of the wall of any of the foregoing heat exchange units, showing a series of blister-like convex 11 and concave 12 indentations pressed into the heat exchange surfaces. The purpose of this arrangement is to cause greater turbulence of the fluid in its flow through the passages, thus increasing its wiping action on the walls. It also increases the area of the heat exchange surface. Both of these factors improve the heat transfer characteristics of the unit.

The blisters are preferably arranged in a staggered pattern to insure that all portions of the fluid stream impinge on them. They are preferably also arranged to alternately protrude from opposite surfaces of the wall, in both its length and width, to further increase the air turbulence and to provide better spacing for the passage of the fluid.

The progressively increasing radius of curvature inherent in the convolute form makes it impractical to preserve a definite relationship between the spacing of protrusions in opposing heat exchange surfaces. For this reason, it is preferred to restrict the maximum depth of such protrusions to not greater than one-half of the normal spacing between the non-protruding portions of the surfaces. If two protrusions should fall in direct opposition, and make contact, such contact will be at only one point and will not materially impede the flow of the fluid. With an arrangement generally similar to that illustrated, the openings between such protrusions will be sufficiently large to care for the necessary fluid flow, as the concave portions of those protrusions facing in the opposite direction will tend to compensate for any restrictions due to the convex portions in a given passage. The use of suitably shallow protrusions with rounded sides as illustrated assists in preventing the formation of pockets of relatively stagnant air, which would otherwise tend to reduce the rate of heat transfer. Such protrusions, having spherical surfaces, preferably extend from the surface a distance of about one-half the radius of the sphere.

This improved heat exchanger surface is easily prepared by passing a sheet of a suitable metal which can be cold worked, such as copper or steel, between closely fitting pressure rolls containing on their surfaces opposed concave and convex portions conforming to the desired blister pattern. The resulting sheet issues from the rolls with the blisters protruding from both surfaces. It may then be simply wound on itself to provide the heat exchanger elements illustrated in any of Figures 1 to 5, 7 and 8. The invention is not limited to the spherical form of blisters illustrated, as such blisters may be relatively shallow concave and convex portions of any other shapes, elliptical, sinusoidal, etc. While relatively smooth curves are preferred, the surfaces may contain minor irregularities relative to the larger blisters.

Figure 7 illustrates an economical closure for the edges of the heat transfer surfaces. Although metallic closures may be used, such as soldered joints or the like, the preferred closure consists of a resilient gasket 13, which may be a sheet of resilient material impervious to the fluid

and capable of withstanding the temperature conditions encountered. A sheet of neoprene or of one of the more flexible Vinylite compositions is suitable material for an ordinary gasket of this type.

Such gaskets may be placed over both ends of the heat exchange unit, such ends comprising the planes containing the longitudinal edges of the heat exchange surfaces 15, and may be held in place by substantially rigid members 16 as backing for the flexible gaskets. The assembly may be held together by suitable mechanical fastening means such as clamps, bolts or the like 29. The rigid members 16 used as backing for the resilient gaskets may be composed of a suitable heat insulating material as may be required for specific applications.

Where a change of phase occurs, as in condensation of moisture from air being cooled as it passes inwardly toward the center of the unit, it is often desirable to remove such separate phase from the unit near its center in order to prevent its passage with the fluid through the outgoing spiral passage. This may be accomplished by providing a suitable conduit or mechanical device, such as an Archimedean screw, where the removal of a solid phase is desired, connecting with the interior of the unit. For example in Figures 7 and 8 the tubes 17 are provided to remove condensed water.

Figure 8 shows the application of this invention in a device for drying air. A blower 18 supplies air through a conduit 20 connecting with entering duct 7. Located in the center of the convolute are heat absorption tubes, or evaporators, 21 of a refrigeration unit comprising a compressor 22, condenser and heat dissipator 23, refrigerant receiver 24, expansion valve 25, refrigerant supply duct 26 and refrigerant return duct 27.

In operation the air supplied by the blower 18 is cooled in duct 4 by indirect heat transfer with the cooled air returning through duct 3. As the air cools to below its dew point, moisture forms on the heat exchanger walls, flows to the bottom of the duct, and is removed through the water drain tubes 17. The air is further cooled by contact with the cooling coils 21 which may be operated to cool the air to 40° F., 32° F. or an even lower temperature. These tubes 21 may have fins 28 (see Figure 7) or may be mounted in a battery through a series of parallel connecting fins as is customary in air radiators and refrigerator condenser units. When operating at temperatures below 32° F., some ice will form on such cooling tubes but by providing sufficient cooling surfaces and capacity, the air stream can be cooled to this temperature or even lower, thereby reducing its moisture content to an extremely low value. Where the unit is intended for intermittent operation, some defrosting can, of course, occur between operating periods, or the cooling tubes may be warmed by bypassing the condenser 23 and expansion valve 25, thus recycling hot compressed refrigerant directly from the compressor 22 to the tubes 21. The chilled and dried air is returned through the duct 3, is warmed by the entering air in duct 4, and leaves the unit at 5 through any suitable connection, dependent upon its intended use. Where warm dry air is desired, the air in duct 5 may be passed over auxiliary heating means, any desired portion of the condenser 23 may be located in this air stream.

It will be understood that the compression

expansion refrigerant cycle shown in Figure 8 is illustrative of only one method for supplying refrigeration in the tubes 21, and that other methods of refrigeration may also be used.

This heat exchanger device, constructed as illustrated in Figure 8 with the heat transfer surfaces 1 and 2 constructed as illustrated in Figures 6A and 6B, has been found extremely efficient in drying air even with a temperature differential between the entering and exit air streams as low as two or three degrees F. In such operation the moisture content of the exit air has approached closely the theoretical moisture content based on the minimum temperature observed in the air stream at the center of the convolute.

I claim:

1. Heat exchange apparatus comprising two substantially parallel heat transfer surface members spaced to provide a first fluid passage between adjacent surfaces, and arranged in substantially the form of a double-wound convolute providing a second fluid passage between the reverse surfaces of said surface members in heat exchange relationship through said surface members with said first fluid passage the said heat transfer surface members comprising closely spaced adjacent concave and convex projections alternating both along the length and the width of said members to provide a continuously curved surface at each of said members.

2. Improved apparatus for heat transfer between two fluid streams comprising two relatively long gas-impervious heat transfer strips of equal width arranged in the general form of a double convolute with substantially parallel surfaces and edges of both strips in the same two planes, closures in both planes for the said edges thereby providing two fluid channels, fluid inlet and exit conduits connecting with each end of each channel, said heat transfer strips comprising closely spaced adjacent concave and convex projections alternating along both the length and the width of said strips.

3. Improved apparatus for heat transfer between two fluid streams comprising two relatively long gas-impervious heat transfer strips of equal width arranged in the general form of a double convolute with substantially parallel vertical surfaces and edges of both strips in the same two planes, closures in both planes for the said edges thereby providing two fluid channels, the inner ends of said channels connecting, means located in said channel near the center of said convolute for transfer of heat between a fluid passing therethrough and a second zone of heat transfer located exteriorly of said convolute, means connecting with the bottom of the central portion of said convolute for separately withdrawing from the fluid passages a new liquid phase formed during the passage of a fluid through the convolute and fluid inlet and exit conduits connecting with the outer ends of said passages.

4. Apparatus according to claim 3 in which said heat transfer surface members comprise closely spaced adjacent concave and convex projections alternating along both the length and

the width of said members to provide a continuously curved surface of each of said members.

5. Apparatus according to claim 3 in which said heat transfer surface members comprise closely spaced adjacent concave and convex projections alternating along both the length and the width of said members, said projections extending not more than half the width of said passages to provide a continuously curved surface of each of said members.

6. Device for drying air comprising a pair of spaced metal strips wound in the form of a convolute about a substantially vertical axis providing an open air passage reversing on itself at the center, closure means on the two edges of the convolute, a heat transfer device having heat absorbing means positioned in said air passage near the center of said convolute connecting with heat releasing means positioned exteriorly of said convolute, a water discharge passage connecting with said air passage at a low point near the center of said convolute, and an air blower connecting with an outer end of said air passage for forcing air therethrough.

7. Apparatus according to claim 6 in which said heat transfer surface members comprise spaced concave and convex projections alternating along both the length and the width of said members to provide a continuously curved surface of each of said members.

8. Apparatus according to claim 6 in which said heat transfer surface members comprise spaced concave and convex projections alternating along both the length and the width of said members, said projections extending not more than half the width of said passages to provide a continuously curved surface of each of said members.

9. A heat transfer element in strip form adapted to be wound on itself without contact of more than a small fraction of adjacent surfaces in any direction comprising a relatively long metal strip continuously curved in alternately spaced adjacent concave and convex portions in both dimensions of the plane of said strip.
